UNITED STATES PATENT OFFICE

2,643,601

WINDOW CONSTRUCTION

Howard Gyorfy, Milwaukee, Wis.

Application April 13, 1948, Serial No. 20,750

3 Claims. (Cl. 98—88)

1 My invention relates to improvements in window construction and more particularly to a ventilator type of window structure.

The object of my invention is to provide a sealed window that is equipped with an integrally constructed ventilator unit.

Another object of my invention is to provide a sealing means for the ventilator unit when stationary louvres are employed.

Still another object of my invention is to provide a self-adjusting means for automatically closing the outer louvres when the inner door of the ventilating unit is closed.

A still further object of my invention is to provide a means for furnishing ventilation without altering the window arrangement.

It will be manifest to anyone familiar with the art that the device as shown, described and claimed herein may be applied to windows that are constructed of a single or double pane arrangement, or used in connection with a storm sash and may be employed to provide air circulation for ventilating purpose with any type of sealed window.

Other and further objects of my invention will become more apparent as the description proceeds and when taken in conjunction with the drawing in which

Figure 1 is a front or outside view of the entire device.

Figure 2 is a cross-sectional view of the assembled device employing stationary louvres taken at the line 2—2 in Figure 1.

Figure 3 is a fragmentary cross-sectional top view of the device as shown in Figure 1.

Figure 4 is a fragmentary cross-sectional view of the tenon arrangement between the panes of glass, and

Figure 5 is a fragmentary cross-sectional view of the ventilator compartment, showing a spring supported around a link arrangement for adjusting the louvres at the outside of the ventilating unit when the inner door is opened or closed.

Similar characters of reference indicate corresponding parts throughout the several views, and referring now to the same, the character 10 shows an outer frame structure into which the panes of glass shown as 11 and 11' are inserted. Obviously, a single glass may be used, or a plurality of panes may be employed. The panes of glass may be of single or double arrangement with air space between them, or a storm sash for extra protection may be inserted into the frame 10. The frame 10 is provided with a sill shown as 12 and forming the bottom of the window

frame proper. This sill 12 is shown covered in part by an inside trim shown as 13 if desired.

The lower portion of the frame 10 below the sill 12 is in the form of an enclosure 14 which constitute a ventilating unit and is open at its inner and outer face, and integrally constructed with the frame 10. The enclosure 14 in Figures 1 and 2 is shown having a front plate 15 provided with integrally constructed louvres 16. This plate 15 is attached to the outer face of the enclosure by means of screws or in any other convenient manner. The ventilating unit or enclosure 14 is provided with a hinged door shown as 17 on the inside thereof, which can be adjusted to suit the convenience of the user.

Although the louvres 16 as shown in Figure 1 and Figure 2 are stationary, to be used in conjunction with a separately operated hinged door 17, which may be placed in either an open or closed position, the ventilating unit or enclosure 14 may be equipped with adjustable louvres actuated by the door 17 as shown in Figure 5, in which a telescopic link arrangement consisting of a tube 19 slidably engaging a tube 19' has a resilient member 22 having its ends disposed between and contacting outwardly projection collars forming a part of the tubes 19 and 19'. The one end of the tube 19' is pivotally connected to a vertical rod 18 at 21' which vertical rod 18 is pivotally connected to the louvre 16 at 18' and the louvre 16 in Figure 5 are shown pivotally mounted at 16' to the vertical supports forming a part of the opening of the ventilating unit or enclosure 14.

35 It will also be manifest to anyone familiar with window construction that the arrangement as shown and specified would permit a sealed and air tight window structure and would provide a device that is depending entirely on the ventilating unit 14 for the circulating of air from the inside to the outside or vice versa, depending on the angle at which the door 17 is set. It is also possible to arrange the hinge 23 on the door 17 so that it would be at the top of the ventilating unit 14 in which case the door 17 would open in the opposite direction from what is shown in Figures 2 and 5 respectively.

Although I have shown a specific type of construction, I am fully cognizant of the fact that 50 many changes in the form and configuration of the structure may be made without effecting its operativeness, and I reserve the right to make such changes as I may deem necessary or convenient without departing from the spirit of my invention or the scope of the appended claims.

Having thus described my invention, what I claim and desire to secure by Letters Patent in the United States is:

1. A window construction of the character described comprising a rectangular frame, panes of glass inserted within said frame, a ventilating compartment integrally constructed within said frame forming a compartment open at its outer and inner face, a plate disposed along the open outer face of said compartment said plate provided with a plurality of louvers pivotally mounted therein, a door forming an enclosure for the inner opening of said ventilating compartment, said door hingedly supported by said frame, and means for adjusting said door to open or close the opening on the inner face of said compartment, a link member, said link member having one end supported by said door and another end supported by said louvers whereby the degree of opening of the louvers is automatically regulated by the degree of opening of said door.

2. A window construction of the character described comprising in combination a rectangular frame, panes of glass inserted within said frame, a sill inserted within said frame in a horizontal fashion at a point above the bottom of said frame, said sill and bottom of said frame forming a ventilating compartment integrally constructed with said frame, said compartment open at its outer and inner face, a plate disposed across the entire face of said ventilating compartment, said plate provided with a plurality of pivoted louvers horizontally disposed, a door forming a closure for the inner opening of said ventilating compartment, said door hingedly attached to said frame, means for adjusting said door to an open and closed position, and a link member pivotally supported by said louvers and

said door and acting as a connecting link for actuating said louvers when said door is actuated.

3. A device of the character described comprising in combination a rectangular window frame, a plurality of panes of glass inserted within said frame, thereby closing the entire area of said frame, a sill portion inserted horizontally within said frame at a point above the bottom thereof, said sill and bottom of said frame forming a ventilating enclosure integrally constructed with said frame, said enclosure open at its outer and inner face, a plate disposed across the open outer face of said ventilating compartment, said plate provided with a plurality of hingedly supported louvers horizontally disposed within said plate, a door member for closing the inner opening of said ventilating compartment, said door hingedly attached to said frame, a link member attached to said hingedly supported louvers and said door, said link member pivotally attached to said louvers and said door to provide actuation of said louvers when said door is actuated, and a resilient means disposed around said link member to compensate for variation in adjustment of said door and louvers in relation to one another.

HOWARD GYORFY.
